(57) **CLAIM**

The ornamental design for a contact lens case, as shown and described.

DESCRIPTION

FIG. 1 is a perspective view of a contact lens case showing my new design;

FIG. 2 is a side elevational view thereof;

FIG. 3 is a side elevational view of the side opposite the side shown in FIG. 2;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of the integral cap and lens support structure of the contact lens case, with the cage doors shown open;

FIG. 9 is a top plan view thereof;

FIG. 10 is a front elevational view thereof;

FIG. 11 is a rear elevational view thereof;

FIG. 12 is a side elevational view thereof, with the cage doors closed;

FIG. 13 is a side elevational view of the side opposite the side shown in FIG. 12, thereof; and,

FIG. 14 is a bottom plan view with the cage doors shown open.

The elements of the claimed design in FIGS. 8–14 are shown separate for clarity and ease of illustration.
